WINDOW CLEANING SEAT

George Lange, Brooklyn, N. Y.

Application January 6, 1937, Serial No. 119,173

18 Claims. (Cl. 304—24)

This invention relates to window seats. More particularly, this invention relates to the type of window seat adapted for use in cleaning the outside of windows in apartment houses and private homes.

One of the objects of my invention is to provide a novel and simplified construction of a folding window cleaning seat of the character described which will automatically adjust itself to slight variations in window sill sizes and which at the same time shall enable a person to clean the windows from the outside thereof with a high degree of safety.

Another object of my invention is to provide a folding window cleaning seat of the character described having novel and simple means of attachment whereby it is adapted for use in connection with different sizes of window sills, which shall comprise relatively few and simple parts, which shall be easy to assemble, relatively inexpensive to manufacture, sturdy and yet light in construction, and which at the same time shall operate with a high degree of efficiency and safety.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is a side elevational view of a window cleaning seat embodying my invention and shown operatively attached to a window sill;

Fig. 2 is a rear elevational view of the Fig. 1 form of device;

Fig. 3 is a sectional view taken substantially on the line 3—3 of Fig. 1;

Fig. 4 is a perspective view of the window cleaning seat illustrated in Fig. 1 but with the window sill omitted; and

Fig. 5 is a side elevational view showing my window seat detached from the window sill and in collapsed or folded position, suitable for storage.

Referring now in detail to Figs. 1 to 4 of the drawing, there is disclosed a window cleaning seat in open, operative position, constructed in accordance with my invention. Said window cleaning seat comprises a base or seat portion 10 which may be of wood, and provided with a

pair of metallic reinforcing members or brackets 11 at opposite ends thereof. The seat 10 may be made of wood, or, if desired, the entire assembly of the seat 10 and members 11 may be of unitary metallic construction. Pivots 13 are provided at the ends of the seat 10 by means of pivots 13 at a point adjacent the rear longitudinal edge of said seat 10, is an inverted U-shaped frame adapted to serve as the back rest B for the window cleaning seat. The back rest B may comprise a pair of arms 15 interconnected at the top by a cross member 17 which may be integral with said arms 15. The back rest B is held in proper position and counter-clockwise movement thereof is limited by the provision of lugs 19 extending inwardly of the lower free ends of the arms 15. The said extended portions 19 are so designed that when the back B is pivotally moved in a counter-clockwise direction a predetermined amount, the said lugs will abut the underside of the brackets 11 and thus prevent further counter-clockwise movement of the back B.

Pivots 21 are provided at the ends of the seat 10 by means of a pivot 21 disposed intermediate the longitudinal edges of the seat 10, are a pair of aligned side supporting members 20. When the window seat is in operative position as shown in the drawing, the side supports 20 are disposed substantially perpendicular to the horizontal plane of the seat 10.

The side supports are designed to hold the window cleaning seat in rigid and safe attachment to the inside window sill, and, therefore, means are provided to limit the clockwise rotational movement of said supports 20. Such means comprise portions 22 extending inwardly from said supports, said lugs being designed to abut the underside of the seat 10 to thus limit the clockwise pivotal movement of said supports 20 about the pivots 21. Pivots 26 are provided adjacent the upper ends of the members 20 by means of pivots 26 are a pair of adjustable arms comprising the interconnected members 25 and 27. To adjustably interconnect the members 25 and 27, they are each provided with a plurality of spaced apertures 31, the apertures in the members 25 being adapted to register with the apertures 31 in the members 27. The members 25 and 27 are held together by any suitable fastening means, such as bolts 32, passing through the pairs of registered apertures 31 and held by wing nuts 32a. The members 27 are provided at their outer ends with hooked portions 28 designed to grip and hold the rounded edge 30 of the inside window sill, as clearly shown in Fig. 1.

To provide additional support for the members 20 and at the same time to facilitate the folding or collapsing of the window seat, there is provided a pair of links 35, each of said links 5 being pivotally fastened at one end thereof to the upper end of a support 20 by means of the pivot 26, while the other end thereof is provided with an elongated slot 36 designed to receive therein an enlarged headed pin 37 fixed to the 10 arm 15. When the back B is in proper operative position, the pins 37 will contact the end of the slots 36 and the links will thus aid the supports 20 in overcoming the pulling strain exerted by the adjustable arms 25, 27.

15 To prevent slipping of the seat 10 on the outer window sill and to provide a safe and rigid grip for the adjustable arms 25, 27 and the hooks 28, I have provided a pair of downwardly projecting rigid members 38 rigidly attached to and having 20 an inclined surface 39 thereof projecting slightly below the lower edges of the brackets 11. The members 38 spaced from the inner longitudinal edge of the seat 10 a predetermined distance, are designed to contact and abut the outer edge of 25 the outside window sill, the inclined surface 39 being adapted to overlie a portion of the top surface of the outer window sill, and the downwardly projecting portions of the members 38 being adapted to overlie a portion of the outer edge of 30 said outer window sill. It is thus seen from Fig. 1 of the drawing that when the window seat is placed in proper position, such as shown, with the hook portions 28 engaging the molding edge 30 and with the arms 25 and 27 properly adjusted as 35 to distance, the members 38 will firmly contact the outer edge of the outer window sill, and since the supports 20 will be prevented from further rotation by the lugs 22 and the slotted links 35, it is seen that the entire assembly will be safely 40 and firmly held in position.

It is noted that the seat 10 will be prevented from being raised to dislodge the members 38 from their position, due to the weight of the person seated thereon.

45 My novel construction is so designed that when the hooked portions 28 are in engagement with the inside window sill and the seat 10 properly positioned, the said seat 10 will pivotally rock about the pivots 26. The result of this construction 50 is such that the window cleaning seat constructed in accordance with my invention is adapted to automatically adjust itself to slight variations in distances between the inside and outside edges of the window sill of different windows.

55 My window cleaning seat as above described is designed to be folded into a compact unit for storage, as illustrated in Fig. 5 of the drawing. To fold the seat into the position as shown in 60 said Fig. 5, it is merely necessary to slightly loosen the wing nuts 32a, and then fold the members 27 to lie adjacent the members 25. The links 35 are then slidably moved backwardly to cause the supports 20 to rotate on the pivots 21 until 65 they are caused to be adjacent the members 25 and 27. After this has been done the back B is pivotally swung down to lie adjacent the top surface of the seat 10.

70 It will thus be seen that there is provided a device in which the several objects of this invention are achieved, and which is well adapted to meet the conditions of practical use.

75 As various possible embodiments might be made of the above invention, and as various changes might be made in the embodiment above set forth,

it is to be understood that all matter herein set forth or shown in the accompanying drawing is to be interpreted as illustrative and not in a limiting sense.

Having thus described my invention, I claim as 5 new and desire to secure by Letters Patent:

1. A folding window cleaning chair of the character described, adapted to be attached to a window sill, comprising a seat member, a back pivotally attached to said seat, a pair of aligned 10 support members each pivotally attached at one end thereof to said seat, a pair of adjustable arms each pivotally attached at one end thereof to the free end of one of said support members and being provided at the other end thereof with a 15 grasping portion adapted to engage the edge of the inside window sill, and means to stabilize each of said supports in operative position.

2. A folding window cleaning chair of the character described, adapted to be attached to a window sill, comprising a seat member, a back pivotally attached to said seat, a pair of aligned 20 support members each pivotally attached at one end thereof to said seat at a point intermediate the longitudinal edges of said seat, a pair of adjustable arms each pivotally attached at one end thereof to the free end of one of said support members and being provided at the other end thereof with a grasping portion adapted to engage the edge of the inside window sill, and 25 means to stabilize each of said supports in operative position.

3. A folding window cleaning chair of the character described, adapted to be attached to a window sill, comprising a seat member, a back pivotally attached to said seat, a pair of aligned 35 support members each pivotally attached at one end thereof to said seat at a point intermediate the longitudinal edges of said seat and adapted, when in operative position to extend upwardly 40 above said seat, a pair of adjustable arms each pivotally attached at one end thereof to the free end of one of said support members and being provided at the other end thereof with a grasping portion adapted to engage the edge of 45 the inside window sill, and means to stabilize each of said supports in said operative position.

4. A folding window cleaning chair of the character described, adapted to be attached to a window sill, comprising a seat member, a back comprising 50 an inverted U-shaped frame pivotally attached to said seat, a pair of aligned support members each pivotally attached at one end thereof to said seat at a point intermediate the longitudinal edges of said seat and adapted, when 55 in operative position to extend upwardly above said seat, a pair of adjustable arms each pivotally attached at one end thereof to the free end of one of said support members and being provided at the other end thereof with a grasping 60 portion adapted to engage the edge of the inside window sill, and means to stabilize each of said supports in said operative position.

5. A folding window cleaning chair of the character described, adapted to be attached to a window sill, comprising a seat member, a back comprising 65 an inverted U-shaped frame pivotally attached to said seat, means for limiting the outward pivotal movement of said back, a pair of aligned support members each pivotally attached 70 at one end thereof to said seat at a point intermediate the longitudinal edges of said seat and adapted, when in operative position to extend upwardly above said seat, a pair of adjustable arms each pivotally attached at one end thereof 75

to the free end of one of said support members and being provided at the other end thereof with a grasping portion adapted to engage the edge of the inside window sill, and means to stabilize each of said supports in said operative position.

6. A folding window cleaning chair of the character described, adapted to be attached to a window sill, comprising a seat member, a back comprising an inverted U-shaped frame pivotally attached to said seat, a pair of aligned support members each pivotally attached at one end thereof to said seat at a point intermediate the longitudinal edges of said seat and adapted, when in operative position to extend upwardly above said seat, a pair of adjustable arms each pivotally attached at one end thereof to the free end of one of said support members and being provided at the other end thereof with a grasping portion adapted to engage the edge of the inside window sill, means for limiting the outward pivotal movement of said back comprising a lug extension on the free ends of said U-frame and adapted to abut the underside of said seat, and means to stabilize each of said supports in said operative position.

7. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edge of said seat and adapted, when in operative position to extend upwardly above said seat, means for limiting the pivotal movement of said support members, a pair of adjustable arms each pivotally attached at one end thereof to the free end of one of said support members and being provided at the other end thereof with a grasping portion adapted to engage the edge of the inside window sill.

8. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edge of said seat and adapted, when in operative position to extend upwardly above said seat, means for limiting the pivotal movement of said support members comprising a lug extending from the edge of said support nearest the pivot and adapted to abut the underside of said seat, and a pair of adjustable arms each pivotally attached at one end thereof to the free end of said support members and being provided at the other end thereof with a grasping portion adapted to engage the edge of the inside window sill.

9. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat and adapted, when in operative position to extend upwardly above said seat, a pair of links each interconnecting one of said supports and said back, a pair of adjustable arms each pivotally attached at one end thereof to the free end of one of said support members and being provided at the other end thereof with a grasping portion adapted to engage the edge of the inside window sill.

10. A folding window cleaning chair of the character described, adapted to be attached to a

window sill, comprising a seat member, a back pivotally attached to said seat, a pair of aligned support members each pivotally attached at one end thereof to said seat at a point intermediate the longitudinal edges of said seat and adapted, when in operative position to extend upwardly above said seat, a pair of links each interconnecting one of said supports and said back, each of said links being pivoted at one of the ends thereof to the upper end of one of said supports and provided at the other end thereof with a longitudinal slot having received therein a pin fixed to said back, a pair of adjustable arms each pivotally attached at one end thereof to the free end of one of said support members and being provided at the other end thereof with a grasping portion adapted to engage the edge of the inside window sill.

11. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat and adapted, when in operative position to extend upwardly above said seat, a pair of adjustable arms each pivotally attached at one end thereof to the free end of one of said support members and being provided at the other end thereof with a grasping portion adapted to engage the edge of the inside window sill, each of said arms comprising a pair of members having portions thereof overlapping at a point intermediate the ends of said arms, and means to stabilize each of said supports in said operative position.

12. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat and adapted, when in operative position to extend upwardly above said seat, a pair of adjustable arms each pivotally attached at one end thereof to the free end of one of said support members and being provided at the other end thereof with a grasping portion adapted to engage the edge of the inside window sill, each of said arms comprising a pair of members having portions thereof overlapping at a point intermediate the ends of said arms, said overlapping portions being provided with registering apertures, and means to stabilize each of said supports in said operative position.

13. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat and adapted, when in operative position to extend upwardly above said seat, a pair of adjustable arms each pivotally attached at one end thereof to the free end of one of said support members and being provided at the other end thereof with a grasping portion adapted to engage the edge of the inside window sill, each of said arms comprising a pair of members having portions thereof overlapping at a point intermediate the ends of said arms, said overlapping portions being provided with registering apertures, means cooperating with said registered apertures for interconnecting said pairs of overlapping members, and

means to stabilize each of said supports in said operative position.

14. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat, a pair of adjustable arms each pivotally attached at one end thereof to the free end of one of said support members and being provided at the other end thereof with a grasping portion adapted to engage the edge of the inside window sill, a rigid member on said seat projecting downwardly therefrom and adapted to abut the outside edge of said window sill, and means to stabilize each of said supports in operative position.
15. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat, a pair of adjustable arms each pivotally attached at one end thereof to the free end of one of said support members and being provided at the other end thereof with a grasping portion adapted to engage the edge of the inside window sill, a rigid member on said seat projecting downwardly therefrom and adapted to abut the outside edge of said window sill, and means to stabilize each of said supports in operative position.
16. A folding window cleaning chair of the character described, adapted to be attached to a window sill, comprising a seat member, a back pivotally attached to said seat, a pair of aligned support members each pivotally attached at one end thereof to said seat at a point intermediate the longitudinal edges of said seat, a pair of adjustable arms each pivotally attached at one end thereof to the free end of one of said support

members and being provided at the other end thereof with a grasping portion adapted to engage the edge of the inside window sill, a pair of rigid members on said seat, projecting downwardly therefrom being adapted to abut the outside edge of said window sill, each said rigid member being disposed adjacent one of the end edges of said seat at a point intermediate said support members and the front longitudinal edge of said seat, and means to stabilize each of said supports in operative position.

17. A folding window cleaning chair of the character described, adapted to be attached to a window sill, comprising a seat member, a back pivotally attached to said seat, a pair of aligned support members each pivotally attached at one end thereof to said seat at a point spaced rearwardly from the front of said seat and adapted when in operative position to extend upwardly above said seat, means for limiting the pivotal movement of said support members comprising a lug on each of said support members and adapted to abut said seat, and a pair of adjustable arms each pivotally attached at one end thereof to the free end of one of said support members and being provided at the other end thereof with a grasping portion adapted to engage the edge of the inside window sill.

18. A folding window cleaning chair of the character described, adapted to be attached to a window sill, comprising a seat member, a back pivotally attached to said seat, a pair of aligned support members each pivotally attached at one end thereof to said seat, a pair of adjustable arms each pivotally attached at one end thereof to the free end of one of said support members and being provided at the other end thereof with a grasping portion adapted to engage the edge of the inside window sill, and means for interconnecting each of said support members with said back, said last named means comprising a pair of links respectively pivotally mounted at one of their ends, and provided at the opposite ends with longitudinal slots adapted to receive therein fixed pins.

GEORGE LANGE. 45
